UNITED STATES PATENT OFFICE

106,793

DESIGN FOR A TUMBLER OR SIMILAR ARTICLE

Curtis B. Ilgenfritz and Edwin E. Slick, Jr., Pittsburgh, Pa., assignors to United States Glass Company, Pittsburgh, Pa., a corporation of Pennsylvania

Application June 22, 1937, Serial No. 69,984

Term of patent 7 years

To all whom it may concern:

Be it known that we, Curtis B. Ilgenfritz and Edwin E. Slick, Jr., citizens of the United States, residing at Pittsburgh, county of Allegheny, in the State of Pennsylvania, have invented a new, original, and ornamental Design for a Tumbler or Similar Article, of which the following is a specification, reference being had to the accompanying drawing, forming a part thereof, in which the figure is a perspective view of a tumbler showing our design.

We claim:

The ornamental design for a tumbler or similar article, substantially as shown.

EDWIN E. SLICK, JR.
CURTIS B. ILGENFRITZ.
